GARMENT HANGER

Frank Key and Elvin S. Land, Neosho, Mo.

Application May 18, 1933, Serial No. 671,750

2 Claims. (Cl. 24—253)

This invention relates to an improved garment hanger and seeks, among other objects, to provide a device of this character which will engage a garment and effectually support it in a hanging position so that the garment will be protected from soiling, and may be retained well pressed.

Another object of the invention is to provide a garment hanger which is particularly adapted for use in conjunction with coat hangers and may be readily engaged upon the lower rail of such a coat hanger.

Our invention seeks, as an additional object, to provide a garment hanger wherein one of the jaws employed is extended and bent to form a hook and the other of said jaws is extended to form a combined thumb lug and stop for limiting opening movement of the jaws.

A further object of the invention is to provide a garment hanger, the jaws of which will engage the cloth of a garment in such a manner that danger of mutilation of the garment will be practically eliminated.

And a still further object of the invention is to provide a garment hanger which will be characterized by the utmost simplicity so that cheapness in manufacture will be a keynote.

Other and incidental objects of the invention, not discussed hereinbefore will be apparent as the description of the invention continues.

In the drawing forming part of our application, Figure 1 is a perspective view showing a pair of our improved garment hangers in position on a coat hanger and supporting a pair of trousers.

Figure 2 is an enlarged vertical sectional view of our device taken on the line 2—2 of Figure 4 and looking in the direction indicated by the arrows.

Figure 3 is a front view of our device,

Figure 4 is a transverse sectional view taken on the line 4—4 of Figure 2, and

Figure 5 is a fragmentary transverse sectional view taken on the line 5—5 of Figure 2.

Referring now more particularly to the accompanying drawing wherein like numerals of reference indicate like parts throughout the several views, the numeral 1 indicates a conventional wire coat hanger which is provided with a straight bottom portion 2. Our improved garment hanger comprises companion jaws which are indicated in general by the numerals 3 and 4. The jaws are formed from strips of relatively thick metal and, as best seen in Figure 2 of the drawing, the jaw 3 is provided with a slightly inwardly inclined garment-engaging portion 5 and a straight central

portion 6. The jaw 3 is bent upon itself, at its upper end portion, to define a hook 7 terminating in a straight end portion 8. The jaw 3 is provided medially of the central portion 6 with upstanding parallel ears 9. The ears are preferably formed on the jaw integrally, the jaw being stamped from a single piece of metal and the ears being afterwards bent into the desired position. The jaw 3 is provided, at the lower end of the central portion 6, and medially of its width, with a loop 10 which is preferably formed by slitting the jaw longitudinally and pressing out the portion between the slits. Carried on the inner face of the garment-engaging portion 5 is a pad 11 which is formed of soft cushioning material. The pad 11 will serve to prevent accidental tearing of the garment abutting the jaws.

The companion jaw 4 is mounted to cooperate with jaw 3 and is provided with an inclined garment-engaging portion 12 which is adapted to 20 coact with the garment-engaging portion 5 of the jaw 3. A pad 13, which is of felt, or other soft material, is placed on the inner face of the jaw 4 and, like the pad 11, will protect the garment from accidental tearing. The jaw 4 is provided 25 with a straight central portion 14 which is slightly inclined inwardly and is adapted to lie between the ears 9 on the jaw 3. The central portion 14 is limited against lateral movement by the ears 9. The jaw 4 also includes a handle 30 portion 15 which is bent outwardly at a point slightly above the ears 9. The handle portion 15 is adapted for manual engagement so that, when said handle is engaged, the garment-engaging portions 5 and 12 may be separated for engaging 35 the fabric of a garment to be supported.

A loop 16, of similar construction to the loop 10 and disposed oppositely thereto, is formed in the straight central portion 14 of the jaw 4.

Connecting the jaws 3 and 4 is a coiled spring 40 17 which is disposed between the ears 9 and between the straight central portions 6 and 14 of the jaws 3 and 4, respectively. The coiled spring 17 is provided with arms 18 and 19 at each end thereof, the arm 18 extending through the loop 16 45 and the arm 19 extending through the loop 10. It will be seen, therefore, that the tension of the spring 17 will prevent spreading of the jaws 3 and 4 at the central portions, and the body of the spring will serve as a spacer for spacing the 50 central portions of the jaws a suitable distance apart. The spring 17 will, moreover, provide a fulcrum, or pivot, for the central portion 14 of the jaw 4 to rock upon. The central portion will, of course, be maintained in position with the 55

coils of the spring by virtue of the fact that the arm 18 is secured in the loop 16 and exerts a continuous downward tension upon the portion 14 of the jaw 4. It will be seen that the jaw 4 is 5 operatively connected with the jaw 3 but is shiftable independently thereof. Great flexibility in operation of the device is, therefore, permitted. It is obvious that the spring 17 effectually connects the jaws.

- 10 In use, after a coat and vest have been suspended on the coat hanger 1, and it is desired to support the trousers on the hanger, the garment-engaging portions are spread apart for engagement with the cuff of the trousers, when the handle portion of the jaw 4 is released for permitting the jaws 3 and 4 tightly to clamp the cuff in position. The jaws are of such length that the entire cuff will be grasped thereby. Danger of slipping of the cuffs from the hanger is thereby 15 eliminated. The trousers are then suspended on the lower portion 2 of the hanger 1 by means of the hook 7 which is engaged over said lower portion. It will be seen that the trousers will be 20 effectually supported so that the crease thereof may be maintained in good shape and the trousers may be carried, together with the coat and vest, so that danger of misplacing said trousers from the coat and vest will be largely eliminated. 25 As best seen in Figures 1 and 2 of the drawing, the hook 7 is so formed that a crotch 7' will be defined. The lower portion 2 of the hanger 1 will engage in the crotch and will effectually limit the garment hangers against longitudinal shifting movement on the coat hanger. Danger of 30 said hangers shifting toward each other is thereby prevented.

Attention is invited to the fact that, as the hook 7 is provided with a straight end portion 8, said straight end portion will serve as a stop 40 and therefore limit inward swinging travel of the handle 15. Undue straining of the spring 17, with

danger of displacement thereof from between the jaws, will be practically eliminated.

Attention is further invited to the fact that, as the garment-engaging portions 5 and 12 are provided with pads 11 and 13, danger of mutilation or tearing of the cuff of the trousers will 5 be practically eliminated.

The device may be made with the utmost facility, it being necessary only to stamp the two jaws from sheet metal, provide the spring, and 10 place the parts in the desired assembled position.

It is believed that the device may be manufactured cheaply on a large scale and it is furthermore believed that the device will find a 15 ready use.

Having thus described our invention, we claim:

1. A device of the class described including jaws, one of said jaws being provided with ears, a loop formed on the jaw, the other of said jaws 20 being provided with a loop and a handle portion and being positioned between the ears, said ears limiting said second-mentioned jaw against lateral displacement, a spring positioned between the ears and between the jaws and having its 25 end portions extending through the loops for operatively connecting the jaws, and pads carried by the jaws and adapted for engagement with an article.

2. A garment hanger including jaws, one of 30 said jaws being formed with ears straddling the other of said jaws for preventing lateral displacement thereof, loops formed on the jaws, a spring disposed between the jaws and having end portions extending through the loops, said spring 35 operatively connecting the jaws and providing a fulcrum whereby the jaws may be rocked with respect to each other, said jaws cooperating for engaging an article.
